UNITED STATES PATENT OFFICE.

HERBERT HEIDELBERG ORR, OF HATTIESBURG, MISSISSIPPI.

STOVEPIPE-COUPING.

No. 796,084.

Specification of Letters Patent.

Patented Aug 1, 1905.

Application filed January 30, 1905. Serial No. 243,392.

To all whom it may concern:

Be it known that I, HERBERT HEIDELBERG ORR, a citizen of the United States, residing at Hattiesburg, in the county of Perry and State of Mississippi, have invented a new and useful Stovepipe-Coupling, of which the following is a specification.

This invention relates to stovepipe-couplings.

The object of the invention is without increasing the cost of producing such couplings or rendering them intricate of construction, and thus difficult of assemblage, to cause the connection or union of the couplings to be more positive in character and practically free from possibility of becoming accidentally disconnected from any cause when once assembled.

With the above and other objects in view, as will appear as the nature of the invention is better understood, the same consists in the novel construction and combination of parts of a stovepipe-coupling, as will be hereinafter fully described and claimed.

In the accompanying drawings, forming a part of this specification, and in which like characters of reference indicate corresponding parts, Figure 1 is a view in elevation, showing two sections of stovepipe that combine to produce one form of coupling. Fig. 2 is a fragmentary sectional detail view through the coupling formed by the sections shown in Fig. 1. Fig. 3 is a view similar to Fig. 1, showing the two sections of stovepipe that combine to produce a slightly-modified form of coupling. Fig. 4 is a fragmentary sectional detail view through the coupling formed by the sections shown in Fig. 3.

Referring to the drawings, 1 designates a part of a section of stovepipe, and 2 practically a complete section thereof. Each section is crimped at one end, as at 3, to adapt it to fit within the end of the adjacent section, and the crimped portion is provided with a plurality of lugs 4—in this instance four—that are rhomboidal in shape. The lugs are adapted to interlock with sockets 5 on an adjacent section of pipe, the sockets as well as the lugs being formed by stamping outward the metal of the pipe-sections, as shown in Fig. 2.

As exhibited in Fig. 1, the sockets are L-shaped, and their longer members 6 and shorter members 7 are disposed obliquely with respect to the axis of the section. As above stated,

the lugs are approximately rhomboidal in form, and their sides are obliquely disposed with respect to the axis of the pipe-section to cause them to engage with the walls of the shorter socket member 7 and exert a drawing action when the pipe-sections are assembled and turned, thereby to force the bead or collar 8, arranged at the base of the crimped portion, against the end of an adjacent pipe-section and form thereby a close joint. By the oblique disposition of the two members of the sockets a twisting action will be necessary, first, to insert the lugs within the socket members 5 and then seat them within the socket members 7, and by this manner of assembling the parts it will be seen that even should the lug's work out of the socket members 7 owing to the oblique disposition of the socket members 5 there will be such resistance to further movement as to cause the pipe-sections to resist any tendency to accidental separation. The drawing feature referred to is one of importance, inasmuch as a closer and more stable union will be secured between the pipe-sections and the bead 8 than could possibly be effected if the members 7 of the sockets were disposed in a line parallel with the cross diameter of the pipe-section.

In the form of the invention shown in Figs. 3 and 4 the sockets 9 are triangular in cross-section and the locking-lugs 10 are conical; but owing to the angular disposition of the two members of the sockets 9 the same locking and drawing features are present as with the form of the invention shown in Figs. 1 and 2.

It will be seen from the foregoing description that although the improvements of the present invention are simple in character that they will in a thoroughly efficient and practical manner secure the results desired and, further, that their addition to the pipe-sections will add no objectionable cost to their manufacture.

Having thus described the invention, what is claimed is—

1. A stovepipe-section provided with approximately L-shaped locking-sockets, the members of which are disposed obliquely with respect to the axis of the section.

2. A stovepipe-section provided at one end with approximately L-shaped sockets, the members of which are disposed obliquely with respect to the axis of the section, and at its other end with rhomboidal locking-lugs.

3. A stovepipe-section provided at one end with approximately L-shaped sockets, the members of which are disposed obliquely with respect to the axis of the section, and at its other end with rhomboidal locking-lugs the sides of which are obliquely disposed with respect to the axis of the section.

In testimony that I claim the foregoing as my own I have hereto affixed my signature in the presence of two witnesses.

HERBERT HEIDELBERG ORR.
